LASTING MACHINE

William Arthur Barker and Harold Lane,
Leicester, England, assignors to United Shoe
Machinery Corporation, Borough of Fleming-
ton, N. J., a corporation of New Jersey

Application December 28, 1938, Serial No. 248,057
In Great Britain March 22, 1938

16 Claims.

(Cl. 12—14)

This invention relates to lasting machines, and more particularly to end-lasting wipers for use in such machines. The invention is herein illustrated as embodied in wipers intended to be utilized in a heel-end lasting machine of the character disclosed in United States Letters Patent No. 1,949,539, granted on March 6, 1934 upon an application of Joseph Gouldbourn, Fred Ricks, and William T. B. Roberts, but it is not limited to machines of that particular character or to machines for lasting the heel ends of shoes as distinguished from the toe ends.

The wipers disclosed in the above-mentioned Letters Patent have been modified heretofore, as disclosed in United States Letters Patent No. 2,082,837, granted on June 8, 1937 upon an application of Harold Lane and John W. Pratt, to provide them at their forward ends (i. e., the ends nearest the shank portion of the shoe) with wiping members which are yieldable laterally of the shoe relatively to other wiping portions of the wipers, so that the wipers may be closed inwardly as far as desired without danger of damage to the machine by reason of interference between their forward end portions. Such a construction is particularly advantageous when, as disclosed in the last-mentioned Letters Patent, the wiping edges of the forward end portions of the wipers are curved inwardly lengthwise of the shoe to prevent the margin of the upper from being crowded unduly forward in the wiping operation and operate upon portions of the upper extending somewhat forwardly of the heel seat where the bottom of the shoe is comparatively narrow. An object of the present invention is to insure that such yieldable end-wiping members will not yield too soon in the wiping operation by reason of pressure of the shoe materials against them, and therefore not wipe inwardly as far as they should the portions of the margin of the upper which they engage. For the purpose in view, as herein shown, there is associated with each of the yieldable wiping members a device which locks it positively against yielding until the wipers are near the limits of their inward wiping movements over the shoe bottom, whereupon the locking devices release the yieldable wiping members and thus permit them to yield during further inward movements of the main portions of the wipers.

The wipers disclosed in both the above-mentioned Letters Patent are provided with forward end portions which may yield heightwise of the shoe relatively to other wiping portions thereof in response to pressure of the shoe upon them if, for example, their end portions should encounter in the wiping operation the lip of a welt shoe insole or should wipe the upper over a portion of an insole which is curved heightwise of the shoe from the heel seat forwardly in the manner characteristic of some shoes provided with high heels.

In the wipers disclosed in Letters Patent No. 2,082,837 such yieldable end portions include the above-mentioned laterally yieldable wiping members. In accordance with a further feature of the present invention, the wipers herein shown are provided with end portions which are yieldable heightwise of the shoe by swinging movements relatively to the main portions of the wipers, instead of by rectilinear movements as heretofore, so as to preserve a substantial continuity between the wiping faces of the end portions and the main portions of the wipers and thus insure adequate pressure on the margin of the upper immediately adjacent to the main portions while avoiding any danger of marking the upper where these portions terminate.

The above and other features of the invention, including various novel details of construction and combinations of parts, will now be more particularly described with reference to the accompanying drawings and thereafter pointed out in the claims.

In the drawings,

Fig. 1 is an inverted plan view of wipers constructed in accordance with one embodiment of the present invention, with the wipers in fully retracted relation to the heel end of a shoe indicated diagrammatically by dot-and-dash lines;

Fig. 2 is a view similar to Fig. 1, but showing the wipers in their fully closed relation to the shoe;

Fig. 3 is an inverted plan view, on a larger scale than Fig. 1, of a detachable end portion of the left-hand wiper shown in that figure

Fig. 4 is a section on the line IV—IV of Fig. 3;

Fig. 5 is a side elevation of the parts shown in Fig. 3, as viewed in the direction of the arrow V in that figure;

Fig. 6 is a section on the line VI—VI of Fig. 3;

Fig. 7 is an inverted plan view of a detachable end portion of one of the wipers constructed in accordance with another embodiment of the invention;

Fig. 8 is a side elevation of the parts shown in Fig. 7, as viewed in the direction of the arrow VIII in that figure; and

Fig. 9 is an elevation of the parts shown in Fig. 7, as viewed in the direction of the arrow IX in that figure.

With reference first to the construction shown in Figs. 1 to 6, inclusive, the wipers comprise blocks 1 and 3 which serve as the main upper-engaging portions thereof, substantially as in the construction shown in Letters Patent No. 2,082,837, these blocks being supported and operated in the manner fully disclosed in Letters Patent No. 1,949,539. Fastened on the forward ends of these blocks are end pieces 5 and 7, each secured to its block by a screw (not shown) and further positioned by a dowel pin 11, these end

5 pieces being detachable to adapt the wipers better for use on comparatively small shoes. Formed in each of the detachable end pieces are two tack driver passages, one of which is shown in dotted lines at 13 in Fig. 4, similar to driver passages in the wiper blocks, and also tack-supplying passages leading to these driver passages, one of the tack-supplying passages being shown in dotted lines at 15 in Fig. 4. The driver passages 13 have 10 in them spring-pressed balls, one of which is shown at 17 in Fig. 4, which support the tacks in positions to be driven by the corresponding tack drivers.

15 In the construction herein shown each of the detachable end pieces 5 and 7 has secured to it by a screw 19 a plate 21 provided with an arcuate guide 23 which lies in a corresponding guideway formed in a wiping member 25 arranged to serve as a continuation of the main wiping portion of 20 the wiper, the guide and guideway being curved about an axis, indicated at 27 in Fig. 5, lying near the forward end of the corresponding wiper block 1 or 3 and near the plane of the wiping face of the block. The wiping member 25 has 25 secured thereon a plate 29 engaged by one end of a spring 31 the other end of which lies in a bore in the end piece 5 or 7. The spring normally holds the plate 29 against a face 33 on the end piece, with the member 25 in a position 30 in which its wiping face is in the same plane as the wiping face of the wiper block, but permits the member 25 to swing heightwise of the shoe about the axis 27 in response to pressure of the shoe materials against it. The wiping member 35 25 corresponds to the member 11 shown in Letters Patent No. 2,082,837 and has pivoted to it by a normally vertical stud 35 a wiping member 37 integral with the stud, this member corresponding to the member 39 shown in the last-mentioned Letters Patent. The wiping member 40 37 is normally positioned with a face 41 thereon in engagement with a face 43 on the member 25 by a spring 45 one end of which lies in a recess 47 formed in a portion 49 of the member 25 and the other end in a recess 51 in the member 37. The wiping member 37 may yield laterally of the shoe about the axis of the stud 35 against the resistance of the spring 45, and since the stud 35 is carried by the wiping member 25, both 45 the members 25 and 37 are yieldable as a unit heightwise of the shoe about the axis 27. The above-mentioned plate 29 extends into a recess in the wiping member 37 to hold this member from falling, while permitting it to swing about the axis of the stud 35.

50 Mounted in a recess in each of the wiping members 37 is a pawl 53 pivoted on a pin 55. This pawl is arranged normally to lie in a notch 59 formed in the portion 49 of the wiping member 25, and thus to prevent the wiping member 37 from yielding about the axis of the stud 35. The pawl has a tail portion 61 engaged by one end of a spring 63 the other end of which lies in a recess in the wiping member 37, this spring 65 normally holding the pawl in the notch 59. When the wipers are closed inwardly toward each other the wiping members 37 are therefore first held by the pawls 53 from yielding laterally of the shoe relatively to the members 25 and the wiper blocks 1 and 3, so that their inwardly curved edges 65 wipe the margin of the upper inwardly over the insole in an unyielding manner. Insurance is thus afforded that the members 37 will be carried inwardly over the shoe bottom 70 as far as is desirable. Near the end of the 75

5 closing movements of the wipers, however, the tail portions 61 of the pawls 53 are carried into engagement with each other, whereupon the pawls are swung out of the notches 59 as the wipers continue their inward movements, thus permitting the members 37 to yield and to remain stationary during further movements of the wiper blocks and the wiping members 25. The swinging of the pawls in response to the pressure of their tail portions 61 against each other is limited by engagement of the tail portions with shoulders 67 on the members 37. If in the course of the wiping operation the wiping members 37 should encounter the lip of a welt shoe insole or should move inwardly over an insole curved at the shank portion in the manner hereinbefore described, these members, together with the members 25, may yield heightwise of the shoe about the axes 27 against the resistance of the springs 31, the positions of these axes being such that in that event substantial continuity is maintained between the wiping faces of the members 25 and the wiping faces of the wiper blocks. Portions of the margin of the upper extending forwardly beyond the wiper blocks will accordingly be wiped over the insole with effective pressure and without any danger of objectionably marking the upper at the junctions of the wiper blocks and the members 25.

10 The embodiment of the invention illustrated in Figs. 7, 8 and 9 is particularly adapted for use in operating on women's shoes which do not require that the detachable wiper end pieces extend so far forwardly as in the case of men's shoes, or that more than a single tack be driven from each of the detachable end pieces. Each of these end pieces in this embodiment comprises two parts 71 and 73 secured together and to the forward end of the corresponding wiper block by a screw (not shown) passing through holes 75 (Fig. 9) in the parts, a dowel pin 77 being further provided for positioning the parts in proper relation to the wiper block. The part 73 has formed in it an arcuate guideway 79 the axis of which, indicated at 81 in Fig. 8, corresponds in location to the axis 27 of the first embodiment hereinbefore described. Slidingly mounted in this arcuate guideway is a rib 83 extending laterally from a wiping member 85 which corresponds to the member 25 of the first embodiment, this wiping member being provided with a single tack-guiding passage 86 thorough which an upper-fastening tack is driven into the shoe. Extending from the wiping member 85 is a lug 87 which lies in a recess 89 in the part 71. The member 85 is further controlled by a spring 91 mounted in a recess 93 in the part 71, this spring holding the member normally in a position determined by engagement of the lug 87 with one wall of the recess 89, while permitting it to swing heightwise of the shoe about the axis 81 in response to pressure of the shoe thereon. It will be understood that a portion of the member 85 is confined between guiding faces on the parts 71 and 73, as will be evident by reference to Fig. 9.

the resistance of a spring 103 which lies at one end in a bore 105 in the member 97 and abuts at the other end against a screw 107 in the member 85. Cooperating with this spring to determine the normal position of the member 97 is a pin 109 mounted in this member and extending into a slot 111 in the member 85, the pin normally engaging the member 85 at one end of the slot, as illustrated in Fig. 7.

Each of the wiping members 97 is normally prevented from yielding laterally of the shoe by a roll 113 which is mounted in a recess in the member and is held normally in wedging engagement with one wall of the guideway 95 and a relatively inclined wall 115 of the recess in which the roll is mounted by means of a spring 117 lying in a bore 119 in the member 97, this spring engaging the roll at one end and an abutment screw 121 at the other end. Slidably mounted in the member 97 is a pin 123 one end of which engages the roll 113 and the other end of which is arranged to engage a similar pin in the opposite wiping member as the wipers are closed inwardly over the shoe bottom. It will be understood that upon such engagement of the two pins with each other, when the wipers have nearly completed their inward movements over the shoe bottom, the end wiping members 97 are unlocked so that they are permitted to yield against the resistance of the springs 103 as the other portions of the wipers complete their inward movements. In this embodiment of the invention the members 97 are thus more readily yieldable in rectilinear directions than they would be if pivotally mounted in the manner of the wiping members 37 of the first embodiment, because their pivots if they were so mounted would necessarily occupy comparatively unfavorable positions. It will be understood that in response to resistance of the shoe the wiping members 85 and 97 may swing heightwise of the shoe about the axes 81 in the same manner as the corresponding wiping members of the construction first described.

In the construction shown in Figs. 7, 8 and 9 each member 71 has in it only a single tack and driver-guiding passage 125 (Fig. 9) in alignment with the passage 86 in the wiping member 85, the tack being supported in this passage in position to be driven by means of a spring 127 which is fastened to the member 71 and extends into the passage 125.

Having described the invention, what we claim as new and desire to secure by Letters Patent of the United States is:

1. In a lasting machine, end-lasting wipers movable inwardly toward each other around an end of a shoe in wiping engagement with the margin of the shoe upper, said wipers having at their forward ends wiping members arranged to yield laterally of the shoe relatively to other wiping portions of the wipers to permit said other portions to move relatively to the end-wiping members in the wiping operation, and locking devices associated with said end-wiping members for preventing such yield thereof until after the wipers have completed a substantial portion of the wiping operation.

2. In a lasting machine, end-lasting wipers movable inwardly toward each other around an end of a shoe in wiping engagement with the margin of the shoe upper, said wipers having at their forward ends wiping members arranged to yield laterally of the shoe relatively to other wiping portions of the wipers to permit said other

portions to move relatively to the end-wiping members in the wiping operation, and locking devices arranged to prevent such yield of the end-wiping members during a portion of the wiping operation and automatically operative in response to the inward movements of the wipers to release said members and permit them to yield during the completion of the wiping operation. 5

3. In a lasting machine, end-lasting wipers movable inwardly toward each other around an end of a shoe in wiping engagement with the margin of the shoe upper, said wipers having at their forward ends wiping members arranged to yield laterally of the shoe relatively to other wiping portions of the wipers to permit said other portions to move relatively to the end-wiping members in the wiping operation, and locking devices arranged to prevent such yield of the end-wiping members during a portion of the wiping operation and movable with the wipers 20 into contact with each other to cause them to release said members and permit them to yield during the completion of the wiping operation.

4. In a lasting machine, end-lasting wipers movable inwardly toward each other around an end of a shoe in wiping engagement with the margin of the shoe upper, said wipers having at their forward ends wiping members movably connected to the other wiping portions of the wipers to permit said other portions to move inward relatively to the end-wiping members in the event of interference of said end members with each other in the wiping operation, springs arranged to control said end-wiping members and yieldable in response to such movement of the other portions of the wipers relatively to the end members, and locking devices also arranged to control said end-wiping members to prevent such movement of the other portions of the wipers relatively to the end members until near 40 the end of the wiping operation.

5. In a lasting machine, end-lasting wipers movable inwardly toward each other around an end of a shoe in wiping engagement with the margin of the shoe upper, said wipers having at their forward ends wiping members movably connected to the other wiping portions of the wipers to permit said other portions to move inward relatively to the end-wiping members in the event of interference of said end members with each other in the wiping operation, springs arranged to control said end-wiping members and yieldable in response to such movement of the other portions of the wipers relatively to the end members, and devices for normally locking 55 said end members to the other portions of the wipers to prevent such movement of the other portions relatively to the end members, said devices being automatically operative to unlock the end members in response to the inward movements of the wipers.

6. In a lasting machine, end-lasting wipers movable inwardly toward each other around an end of a shoe in wiping engagement with the margin of the shoe upper, said wipers having at 65 their forward ends wiping members movably connected to the other wiping portions of the wipers to permit said other portions to move inward relatively to the end-wiping members in the wiping operation, and devices arranged positively to prevent such movement of the other portions of the wipers relatively to the end members during a portion of the wiping operation and thereafter to permit such movement during the completion of the wiping operation. 70 75

7. In a lasting machine, end-lasting wipers movable inwardly toward each other around an end of a shoe in wiping engagement with the margin of the shoe upper, said wipers having at 5 their forward ends wiping members movably connected to the other wiping portions of the wipers to permit said other portions to move inward relatively to the end-wiping members in the wiping operation, and devices for locking said 10 end members to the other portions of the wipers to prevent such movement of the other portions relatively to the end members during a portion of the wiping operation and for automatically unlocking the end members prior to the completion 15 of the wiping operation.
8. In a lasting machine, end-lasting wipers movable inwardly toward each other around an end of a shoe in wiping engagement with the margin of the shoe upper, said wipers having at 20 their forward ends wiping members movably connected to the other wiping portions of the wipers to permit said other portions to move inward relatively to the end-wiping members in the wiping operation, and devices carried by the 25 wipers for locking said end members to the other portions of the wipers to prevent such movement of the other portions relatively to the end members during a portion of the wiping operation, said devices being arranged to be rendered inoperative by contact with each other prior to the completion of the wiping operation.
9. In a lasting machine, end-lasting wipers movable inwardly toward each other around an end of a shoe in wiping engagement with the 35 margin of the shoe upper, said wipers having at their forward ends wiping members movably connected to the other wiping portions of the wipers to permit said other portions to move inward relatively to the end-wiping members in the wiping operation, and pawls carried by the wipers for preventing such movement of the other portions of the wipers relatively to the end members during a portion of the wiping operation, portions of said pawls being movable into engagement with each other to render them inoperative in response to the inward movements of the wipers prior to the completion of the wiping operation.
10. In a lasting machine, end-lasting wipers 50 movable inwardly toward each other around an end of a shoe in wiping engagement with the margin of the shoe upper, said wipers having at their forward ends wiping members movably connected to the other wiping portions of the wipers 55 to permit said other portions to move inward relatively to the end-wiping members in the wiping operation, spring-pressed locking members for preventing such movement of the other portions of the wipers relatively to the end-wiping 60 member during a portion of the wiping operation, and pins arranged to control said locking members and movable by the wipers into contact with each other to render the locking members ineffective prior to the completion of the wiping 65 operation.
11. In a lasting machine, end-lasting wipers movable inwardly toward each other around an end of a shoe in wiping engagement with the margin of the shoe upper, said wipers having at 70 their forward ends wiping members slidably connected to other portions of the wipers by straight guideways extending laterally of the shoe to per-
- mit said other portions to move inward relatively to said end-wiping members upon interference of said members with each other in the wiping operation, and springs arranged to control said end members and against the resistance of which said other portions of the wipers are thus movable relatively to the end members.
12. In a lasting machine, end-lasting wipers movable inwardly toward each other around an end of a shoe in wiping engagement with the margin of the shoe upper, said wipers having at 10 their forward end portions wiping members mounted for swinging movements heightwise of the shoe relatively to other wiping portions of the wipers about axes extending laterally of the 15 shoe in response to pressure of the shoe upon them in the wiping operation.
13. In a lasting machine, end-lasting wipers movable inwardly toward each other around an end of a shoe in wiping engagement with the 20 margin of the shoe upper, said wipers having at their forward end portions wiping members yieldingly movable heightwise of the shoe in the wiping operation relatively to other wiping portions of the wipers about axes extending laterally of 25 the shoe in such locations as to maintain substantial continuity between the wiping faces of said end-wiping members and the wiping faces of said other portions of the wipers notwithstanding such movement of the end members.
14. In a lasting machine, end-lasting wipers movable inwardly toward each other around an end of a shoe in wiping engagement with the margin of the shoe upper, said wipers having at their forward end portions wiping members 35 mounted for movements heightwise of the shoe relatively to other wiping portions of the wipers along arcuate guideways curved about axes extending laterally of the shoe in response to pressure of the shoe upon them in the wiping operation, and springs against the resistance of which said end-wiping members are thus movable.
15. In a lasting machine, end-lasting wipers movable inwardly toward each other around an end of a shoe in wiping engagement with the 45 margin of the shoe upper, said wipers having at their forward end portions wiping members mounted for swinging movements heightwise of the shoe relatively to other wiping portions of the wipers about axes extending laterally of the 50 shoe in response to pressure of the shoe upon them in the wiping operation, and other wiping members mounted to swing heightwise of the shoe with said first-named members, said other members being yieldable laterally of the shoe relatively to said first-named members in the wiping operation.
16. In a lasting machine, end-lasting wipers movable inwardly toward each other around an end of a shoe in wiping engagement with the 60 margin of the shoe upper, each of said wipers having at its forward end portion a pair of wiping members both yieldable heightwise of the shoe relatively to other wiping portions of the wiper about an axis extending laterally of the 65 shoe in response to pressure of the shoe thereon, one member of the pair being also rectilinearly yieldable relatively to the other laterally of the shoe.
